(57) **CLAIM**

The ornamental design for an interior door panel for an automobile, as shown and described.

DESCRIPTION

FIG. 1 is a perspective view of an interior door panel for an automobile showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The claimed design is indicated by the relatively dark portions in the figures. The relatively light portions form no part of the claimed design.
